(57) **CLAIM**

The ornamental design for a portable fitness equipment, as shown and described.

DESCRIPTION

FIG. 1 is a front, left perspective view of a portable type vitality fitness equipment showing my new design;

FIG. 2 is a right side view thereof, the left side view being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken line showing in FIG. 6 is for the purpose of illustrating portions of the portable fitness equipment which form no part of the claimed design.

The broken line showing of portable fitness equipment is for the purpose of illustrating portions of the article and stitching that form no part of the claimed design.
